[57] ABSTRACT

This invention relates to ice tray grids having a combined camming handle and ice tong tool adapted to be detachably applied thereto. The tool performs an ice release camming handle function when used in combination with an ice tray grid to provide sequential release for the ice cubes while also performing as resiliently deflectable ice tongs that may be readily removed from the grid for use in an ice piece serving operation.

ICE TRAY GRID WITH COMBINED CAMPING HANDLE AND DETACHABLE ICE TONG TOOL

This invention pertains to freezing trays and more particularly to a combined freezer tray grid camming handle and detachable ice tong serving tool adapted to be readily removed from the grid.

The prior art as represented by U.S. Pat. No. 2,642,726 issued June 23, 1953 to A. J. Frei, Sr., discloses a mechanically operated freezing tray with a partitioning grid having a hand lever camming directly upon the endmost cross wall of the grid to initiate the releasing operation by loosening the first transverse row of ice blocks, after which the loosening of additional ice blocks requires much less force as explained in detail in the Frei patent. The present invention provides a combined camming handle and detachable ice tong assembly by utilizing the resiliently deflectable nature of the ice tongs such that they may be readily inserted and removed from the grid of a freezer tray. A generally U-shaped tool has off-set appended gripping jaws, which function as the camming portion of the assembly while also serving as the attaching means by virtue of the arms being sprung toward each other to permit pivotal attachment of the jaws to the longitudinal extending portions of the grid.

It is an object of this invention to provide a combined camming handle and detachable ice tong tool adapted to be readily applied to the grid of a freezing tray for camming the transverse walls of the grid and for removable use as ice tongs such as for lifting the ice pieces from the freezing tray.

It is another object of this invention to increase the utility of a freezing tray grid camming handle by providing a combined camming handle and removable ice tong tool formed of a resilient sheet stock bent along a center line and having a closed end loop memory for a pair of spring arms each provided with complementary ice cube grasping jaw thereon, the grasping jaws including grid attaching and pivoting means, and wherein the jaws are configured in off-set fashion to provide cam means engaging a transverse partition of the grid for releasing the ice cubes from the tray.

Further objects and advantages of the present invention will be apparent from the following description, reference being made to the accompanying drawing wherein preferred embodiments of the present invention are clearly shown.

In the drawings:

FIG. 1 is a top view of a freezing tray embodying one form of the invention;

FIG. 2 is a sectional view of the tray taken along the lines 2-2 of FIG. 1;

FIG. 3 is an enlarged view of the outer surface of one of the gripping tongs;

FIG. 4 is a cross section taken on the lines 4-4 of FIG. 3;

FIG. 5 is a fragmentary sectional view taken on the lines 5-5 of FIG. 3 showing modified attaching means;

FIG. 6 is a perspective view of the combined camming handle and ice tong utensil shown engaging an ice piece.

Referring now to the drawings, there is shown the freezing tray in the form of a long rectangular retainer pan 20 having sloping sides surrounded by turn-down rim 22 as disclosed in U. S. Pat. No. 3,380,702 issued Apr. 30, 1968 to R. N. Strahan, assigned to the same assignee as the instant application the disclosure of

which is incorporated by reference herein. Within the pan is a removable grid 24 which includes two longitudinal walls generally indicated at 25 and 26 each having lower wall portions 27 and 28 resting upon the bottom 29 of the pan 20. The longitudinal walls 25, 26 each has an upper slide bar 30, 31 having their lower edges sliding upon the upper edges of the lower portions 27 and 28. The lower portions of these longitudinal walls 25 and 26 preferably diverge apart slightly so as to facilitate the release of the frozen ice cubes from the grid.

The transverse walls 34 of the grid 24 are supported with their bottom edges 36 held above the bottom 29 of the tray at all times by the upper longitudinal bars 30 and 31. The upper longitudinal slide bars 30 and 31 are mounted on top of the lower wall portions 27 and 28 for longitudinal sliding movement relative to each other. A plurality of lanced out tabs 35 are formed on the upper edges of the wall portions 27, 28 to maintain proper sliding contact with the bars 30, 31. The slide bars 30 and 31 may be vertical or inclined similar to the lower wall portions 27 and 28 as shown in the above-mentioned U. S. Pat. No. 3,380,702.

The lower wall portions 27 and 28 are provided with a plurality of spaced notches 38 in their bottom edges which receive webs beneath slots in the transverse movable wall 24 through which extend the longitudinal walls 25 and 26 as shown in the U.S. Pat. No. 3,380,702. These notches 38 face downwardly while the upper bars 30 and 31 are provided with an equal number of similarly spaced upwardly extending notches 44. The bottom of the notches 44 support web portion 46 of the transverse movable walls.

A combined ice release camming lever and ice tong tool, generally shown at 48, is detachably and pivotally supported on the removable grid 24 by suitable means such as by washer-head rivets or the like 50 and 51 extending through holes 52 in the lower portions 27, 28 of the longitudinal walls 25, 26. The front portion of the combined tool 48 when lifted, pivots on the rivets 50, 51 and engages the upper portion of the first transverse wall 34a with the first notch in the slide bars 30 and 31 to move forward notches 44 therein to progressively move the upper portions of the transverse movable partition walls 34a-34e to loosen the cubes from the tray preparatory to dumping or otherwise moving the frozen cubes. Preferably each transverse or cross wall 34b-34d which underlies combined tool 48 when in its attached down position has its central upper edge cut away, as shown at 47 in FIG. 1, to permit combined tool 48 to be partly recessed with the upper edges of the cross walls to facilitate the stacking of the freezing trays one upon the other.

As shown in FIG. 1 the detachable combined tool 48 is generally of a U-shape configuration preferably comprised of sheet material of a springlike nature, such as spring steel or stainless steel having resilient characteristics. The tool has a central finger gripping portion formed by longitudinal flat arm members 60 and 61, shown generally parallel in FIG. 1 when the tool is pivotally attached to the grid, with a keyhole shaped opening having an enlarged hand-gripping looped or closed end portion 64 preferably of parabolic or oval shape whose long axis is transversely arranged relative to the tray. The loop portion 64 has a memory and maintains the arms 60, 61 disposed in outwardly diverging relation in the undeflectable state as shown in FIG. 6. Each of the arms 60, 61 are bent diagonally outwardly at an

angle of about 25° to form shoulders 62, 63 having appended outwardly off-set leg portions 66, 67 terminating in downwardly projecting complementary ice piece gripping jaws 70, 71. In the preferred form the jaws 70 and 71 extend downwardly at an acute angle of about 55° with the horizontal.

As seen in FIGS. 3 and 4 the jaws 70 and 71 are formed with a spoon-shaped or outwardly convex configuration with peripheral edges 74 in opposed alignment. Preferably, the lower portions of the peripheral jaw edges 74 have a series of teeth 76 integrally formed therewith by spaced flutes whereby the inner edges of the teeth provide cutting barbs to grip the ice pieces in a manner indicated in FIG. 6. It will be seen in FIG. 2 that the jaws 70 and 71 are formed in a downwardly projecting manner such that their paired upper edges present smooth arched or curved camming surfaces 72, 73 for engagement with the transverse partition wall 34a to thereby move it from an angular position to a substantially vertical ice release position.

Due to the spring characteristics of the sheet material, the arms 60, 61 are normally in somewhat of an un tensioned or free position diverging outwardly as seen in FIG. 6. When the combined detachable handle and ice tong tool of the present invention is configured and shaped in the preferred manner the two arms 60, 61 must be deflected or pressed together before the jaws 70, 71 will be in position to be pivotally inserted on the pins 82, 84 which in the disclosed form of FIG. 1 are the stem portions of the pair of rivets 50, 51. Consequently, when such resiliently sprung jaws are located such that the pins 82, 84 are inserted in the aligned holes 86 of the jaws and the arms released, there is an increased firm pressure created against lower portions 27 and 28 of the longitudinal grid walls because of the memory of the handle or loop portion 64. This arrangement insures the holding qualities of the tool 48 while enabling it to pivot on the pins 82, 84 to perform its ice release camming function in a manner described in the above mentioned U.S. Pat. No. 2,642,726.

As shown in FIG. 5 an alternate means of pivotally attaching the combined camming lever and ice tong tool to the longitudinal walls 25, 26 of the grid involves the provision of suitable trunnion-like pins extending outwardly from the outer convex surfaces of the modified jaws one of which is indicated at 70'. Preferably the pins, one of which is indicated at 90, are tubular rivets inserted in the hole 86' of jaw 70' providing a smooth ended pin 92 for insertion in one of a pair of aligned pivot holes in the longitudinal walls of a grid with the grid holes having a location substantially the same as the holes 52 for the rivets 50 and 51 shown in FIG. 1. In this form of the invention the pair of jaws can be deflected toward each other sufficiently to permit the two opposed pins 92 to pass down between the two longitudinal walls 25, 26 (in the partition grid assembly described above) into registration with the aligned holes 52 after which the legs 66, 67 are permitted to spring apart and cause pins 92 to project into their pivot holes 52. Thus the combined camming handle and ice tong tool is detachably mounted with the arm portions 60, 61 providing an outwardly directed biasing force against the opposed faces of the longitudinal walls 25, 26 to retain the tool in assembled position. It will be appreciated that the spoon-shaped configuration of the jaws of either form of the invention result in

minimal contact area between the jaws and the longitudinal partitions 25, 26 to provide for free pivotal movement of the tool when used in its ice release mode of operation while insuring clearance between the teeth 76 and the partitions 25, 26.

The combined camming handle and ice tong tool may be optionally made of resilient plastic sheet material or the like bent to form a hairpin turn or molded to form a loop turn similar in shape to the looped 10 closed end 64 shown for the metal handle.

It is to be observed that the combined hand lever and ice tong tool assembly herein contemplated may be provided with insulation gripping pads formed of suitable material such as plastic shown at 94 and 96 in FIG. 15. In the form shown the pads 94, 96 are molded with a channel portion to receive the arms 60 and 61 therein and are fixed thereto by suitable means such as rivets 98. Still another modification involves coating the entire hand gripping portion of the tool assembly with an 20 insulation and decorative coating such as by dipping in a suitable molten plastic coating material.

The combined ice tong tool 48 design facilitates the grasping of the ice pieces in that the downwardly depending or off-set jaws allow the body portion of the 25 tool to be oriented in a horizontal position which allows a similar tray to be readily stacked thereon while in a freezer compartment, for example. Also, when the formed combined tool of the present invention is configured and shaped in the preferred manner the two 30 outwardly diverging arms 60, 61 must be sprung together in either form of the invention. Consequently, when such resiliently sprung jaws are inserted in pivotal fashion with the longitudinal walls of the grid, there is an increased firm pressure created against the walls 25, 35 26 as illustrated and explained. This arrangement as will be apparent to those skilled in the art improves the holding qualities, pivotal movement, and capability as an ice release camming handle afforded by the present invention.

40 Thus the present invention in addition to being inexpensive, easy to fabricate and highly effective in its combined functions as an ice tong tool may provide an additional feature such as having a bottle opener designed into the handle as indicated by the cut-out portion 100 of the handle. It should be noted that the handle 64 could have a configuration other than the oval-shaped loop shown without departing from the scope of the invention. Thus, a handle with angular bend portions or a U-shape design could be used depending upon the material employed and the design of the grid structure.

45 While the embodiment of the present invention as herein disclosed constitutes a preferred form, it is to be understood that other forms might be adopted.

50 55 What is claimed is:

1. A grid for a freezing tray including a pair of spaced longitudinal wall structures each comprising a lower partition wall member and an upper operating member 60 slidably mounted upon the lower member with adjacent edges in contact for relative longitudinal movement, a plurality of transverse partition walls loosely mounted on and supported by said pair of longitudinal wall structures, said transverse walls being spaced lengthwise along said pair of longitudinal wall structures and extending between and on both sides of said pair of longitudinal wall structures to form ice cube compartments between and on the outside of each of

the pair of longitudinal wall structures, each upper operating member having formed therein means embracing and supporting the upper portions of its associated transverse wall structure, camming means for moving said operating members relative to and lengthwise of their associated lower partition wall members to move the upper portions of said transverse walls lengthwise of the lower partition members, wherein the improvement comprises providing said camming means in the form of a combined detachable ice release camming handle and ice tong serving tool, said combined tool formed of resilient sheet material having a bend along a center line to provide a handle, a pair of flat arm members disposed in outwardly diverging relation in their undeflectable state extending from said handle, each said arm member having an integral ice gripping jaw projecting downwardly from its free end, said jaws having their paired upper edges presenting curved camming surfaces for engagement with a transverse partition wall of the grid to thereby move it from an angular position to a substantially vertical ice piece release position, said arm members being resiliently deflectable to spring said jaws inwardly into spaced substantially parallel extending relationship between the lower longitudinal wall members, engagement means on each of said jaws for pivotal attachment with cooperating connecting means on the lower longitudinal wall members whereby the camming surfaces of said jaws operate on one transverse wall upon pivotal movement of the combined tool to move the transverse walls to effect ice cube release from the grid, said arm members being resiliently deflectable for the flexing of said arm members inwardly for ready release from said longitudinal walls whereby said handle has a memory to return said arm members to an outwardly diverging position in their undeflectable state whereby said arm members are operable for flexing said jaws in an ice piece serving operation.

2. In combination with the grid of an ice freezing tray of the type including a pair of spaced longitudinal wall structures each comprising a lower partition wall member and an upper operating member slidably mounted upon the lower member, said grid including a plurality of transverse partition walls loosely mounted on and supported by said pair of longitudinal wall structures to form ice cube compartments between and on the outside of each of the pair of longitudinal wall structures, camming means for moving the operating members relative to and lengthwise of their associated partition wall members to move the upper portions of said transverse walls lengthwise of the lower partition wall members, said camming means in the form of a combined ice release camming handle and detachable ice tong serving tool, said ice tong serving tool having a generally U-shaped configuration formed of a sheet of resilient material having a bend along a center line providing a pair of flat arm members having ice gripping jaw formations on the free ends thereof, each of said jaw formations having a spoon-shaped configuration with their convex surfaces facing away from each other, each of said jaw formations being disposed at a downwardly directed acute angle relative to the plane of extension of said arm members such that their paired upper edges present curved camming surfaces for engagement with a transverse partition wall of said grid to thereby move it from an angular position to a substantially vertical ice cube release position, an opening on each of said jaw

formations for pivotal engagement with respective aligned pin members extending inwardly from said longitudinal partition wall members, said arm members being resiliently deflectable to spring said jaw formations inwardly for engagement of the openings with their associated pin members such that said arms are in spaced substantially parallel extending relationship with said longitudinal partition wall members, said paired camming surfaces of said jaw formations operative on one transverse wall upon pivotal movement of said serving tool to move the partition walls of said grid to effect ice cube release therefrom, said arm members being resiliently deflectable for the flexing of said arm members inwardly for ready detachment from the longitudinal wall members whereby said serving tool having a memory to return said arm members to an outwardly diverging position in their undeflectable state for the flexing of said arm members in an ice cube serving operation.

3. In combination with the grid of an ice freezing tray of the type including a pair of spaced longitudinal wall structures each comprising a lower partition wall member and an upper operating member slidably mounted upon the lower member, said grid including a plurality of transverse partition walls loosely mounted on and supported by said pair of longitudinal wall structures to form ice piece compartments between and on the outside of each of the pair of longitudinal wall structures, each upper operating member having formed therein means embracing and supporting the upper portions of its associated transverse partition wall, camming means for moving the operating members relative to and lengthwise of their associated partition wall members to move the upper portions of said transverse walls lengthwise of the lower partition wall members, said camming means in the form of a combined ice release camming handle and detachable ice tong serving tool, said combined tool having a generally U-shaped configuration formed of a sheet of resilient material having a bend along a center line forming a keyhole-shaped opening including an enlarged loop portion at the closed end, said combined tool providing a pair of flat arm members having ice gripping jaw formations on the free ends thereof, the ends of said arm members having shoulders diverging laterally outwardly from each other to a location such that when said arm members are flexed into parallel relationship the jaw formations are substantially parallel and in juxtaposed relation to the inner opposed surfaces of said longitudinal partition wall members, each of said jaw formations having a spoon-shaped configuration with their convex surfaces facing away from each other, each of said jaw formations being disposed at a downwardly directed acute angle of the order of 55° relative to the plane of extension of said arm members such that their paired upper edges present curved camming surfaces for engagement with a transverse partition wall of said grid to thereby move it from an angular position to a substantially vertical ice cube release position, engagement means on each of said jaw formations for pivotally connecting said combined tool between said longitudinal partition wall members, said arm members being resiliently deflectable to spring said jaw formations inwardly for engagement with their associated longitudinal partition wall members such that said arms are in spaced substantially parallel extending relationship with said longitudinal partition wall members, said

paired camming surfaces of said jaw formations operate on one transverse wall upon pivotal movement of said combined tool to move the partition walls of said grid to effect ice cube release therefrom, said arm members being resiliently deflectable for the flexing of said arm members inwardly for ready detachment from

the longitudinal wall members whereby said combined tool having a memory to return said arm members to an outwardly diverging position in their undeflectable state for the flexing of said arm members in an ice piece serving operation.
